UNITED STATES PATENT OFFICE

2,627,914

FIREPLACE FRONT

Clifford Clayton Helwig, Windsor, Ontario,
Canada

Application July 5, 1949, Serial No. 102,970

2 Claims. (Cl. 160—117)

1

This invention relates to improvements in a fireplace front and appertains particularly to a fixture combining a fire screen and folding door assembly.

An object of the invention is to provide a permanent yet unattached fireplace front that will fit snugly against the face of an open-type fireplace, framing the opening thereof, affording ready access to the grate basket for fueling and cleaning, providing protection against flying sparks or unfriendly flames, resisting accidental displacement and, when the doors are closed, enhancing the beauty of the fireplace while shutting off drafty currents of escaping warm air that normally sweep up the chimney.

A further object of the invention is to provide a combined sectionalized fire screen and foldable door closure embodying novel and improved structural details that add to the utility, convenience and attractiveness of an open fireplace.

A still further object of the invention is the provision of a fixture, of the nature and for the purposes described, that is characterized by structural simplicity, durability, compactness and efficiency and being capable of production and sale at reasonable cost is thereby rendered commercially desirable.

To the accomplishment of these and related objects as shall become apparent as the description proceeds, the invention resides in the construction, combination and arrangement of parts as shall be hereinafter more fully described, illustrated in the accompanying drawings and pointed out in the claims hereunto appended.

The invention will be best understood and can be more clearly described when reference is had to the drawings forming a part of this disclosure wherein like characters indicate like parts throughout the several views.

In the drawings:

Figure 1 is a front elevation of a possible embodiment of the invention applied to a conventional fireplace, the outer doors being shown in "closed" position;

Figure 2 is a similar front elevation with the outer doors folded back, as in "open" position;

Figure 3 is a transverse, horizontal section through the fireplace and fixture; and

Figure 4 is an enlarged vertical sectional detail through the fixture.

The conventional open-type fireplace 1 shown in the drawings is seen to consist of a hearth 2, fireplace opening 3, and fire chamber or basket recess 4.

The novel fixture herein disclosed comprises a 55 ter or accordion style, their added width enabling

2

base plate 5 designed to rest on the hearth 2 with a frame that surrounds the fireplace opening 3 and fits snugly against the face of the fireplace 1. The frame is composed of a pair of opposite side posts 6 and a narrower top bar 7 joining the upper ends of the posts. A decorative hood or plate 8 surmounts the top bar 7. To compensate for slope of the hearth 2 and assure that the frame abuts the fireplace face in close fitting parallel relation, the base plate 5 has a transversely spaced pair of adjustable set-screw-like bolts 9 threaded therethrough to engage the surface of the hearth and by the rotation of which the plumb of the upright frame can be varied to suit. These adjustable bolts are preferably embellished with a decorative notch such as the ball tops 10 to match a similar decoration 11 on the hood or top plate 8.

Supported by the rectangular frame is a sectionalized fire screen comprising a pair of doors of gate-like sections 12 of wire mesh screen outlined with a rod or other reinforcing edge 13. These two screen doors 12 are hingedly connected to the confronting inner faces of the frame posts 6 and have their upper edges overlapping the narrower top bar 7. The screen doors meet at the center of the fireplace opening when closed and are normally fastened by a conventional catch 14. They do not reach to the bottom of the fireplace but terminate well above the base plate 5 so that they may clear the top of the ball top bolts 9 when swung open as for fueling. The bottom horizontal strip of the fixture frame is closed in by a removable, elongated, rectangular screen section 15 that rests in U-shaped channels 16 secured to the opposite inner faces of the frame posts 6 and are inclined outwardly slightly at the top to permit this screen section 15 to be withdrawn when the door sections 12 are closed, as will be seen in Figure 4.

40 In addition to this novel, thoroughly safe and very convenient sectionalized screen, the fixture frame also carries a pair of door closures 17 hinged to the face of the posts 6 at their outer edges. They extend the full height of the open frame and are designed when closed to completely cover and effectively seal the fireplace opening 3. Each of the door closures 17 is formed of two hingedly connected sections or panels 17a and 17b, the former being narrower and at the outside and hinged to the frame posts and the latter being the inner ones, designed to meet and be fastened together when the doors are closed and when opened to overlie the outer narrow doors, in shutter or accordion style, their added width enabling

them to cover also the frame posts 6 for the width thereof. The door sections 17a and 17b being reversely hinged to allow them to fold back conveniently and compactly out of the way against the fireplace, are also permitted by their doubling action to swing past inside the ball-topped adjusting bolts 9, as seen in dotted line on the right side of Figure 3. These door panels may be of any suitable material, brass, copper plate, chromium and heat resisting armoured glass being among the most desirable. In closed position, the doors will preferably nest under the over-hanging forward edge of the hood 8 and fit closely to the base plate 5 thus to effectively reduce or eliminate the usual fireplace drafts and resultant heat losses.

From the foregoing description taken in connection with the accompanying drawings, it will be manifest that a fireplace front is provided that will fulfil all the necessary requirements of such a device, but as many changes could be made in the above description and many apparently widely different embodiments of the invention may be constructed within the scope of the appended claims without departing from the spirit or scope thereof, it is intended that all matters contained in the said accompanying specification and drawings shall be interpreted as illustrative and not in a limitative or restrictive sense.

Having thus described the invention, what is claimed as new is:

1. A fireplace fixture for application to the front face of a fire place comprising a frame outlining a fireplace opening and a sectionalized fire screen therefor, said screen consisting of a pair of half gate sections hinged to the opposite sides of said frame with the lower edge of said sections lying at a level substantially above the bottom of said frame, vertically and outwardly extending channels on the sides of said frame adjacent the

bottom thereof, an elongated screen section positioned in said channels with the upper edge thereof being spaced below and offset forwardly relative to the lower edge of said gate sections whereby said elongated section may be moved vertically and removed from said channels.

2. A fireplace fixture for application to the front face of a fire place comprising a frame outlining a fireplace and a sectionalized fire screen therefor, said frame including a base plate and opposite side posts, said screen consisting of a pair of half gate sections hinged to said side posts with the lower edge of said gate sections lying at a level substantially above the bottom place of said frame, vertically and outwardly extending channels on the side posts of said frame adjacent the lower ends thereof, an elongated screen section positioned in said channels with the upper edge thereof being spaced below and offset forwardly relative to the lower edge of said gate sections whereby said elongated section may be moved vertically and removed from said channels, and plumb adjusting bolts threaded through said base plate for adjusting said frame in said fire place.
